(57) **ABSTRACT**

A pillow for ergonomically supporting a user includes a central supporting pillow having at least two arm support members extending from the central supporting pillow, an adjustable neck support member being cylindrical in shape and having an outer surface, and a bungee cord attached to the neck support member and the central support pillow, wherein the neck support member is freely adjustable and detachably attached using the bungee cord, the bungee cord having one end attached to a top surface of the central supporting pillow and another end attached to the outer surface of the adjustable neck support member to ergonomically support a back and a neck of the user.

CROSS-REFERENCE TO RELATED APPLICATIONS

The present application is a continuation application of U.S. Ser. No. 29/717,095, filed Dec. 13, 2019, which is a continuation application of U.S. Ser. No. 29/622,761, filed Oct. 19, 2017, now U.S. Design Patent No. D875,432, issued Feb. 18, 2020, and is a continuation-in-part application of U.S. patent application Ser. No. 15/849,702, filed Dec. 21, 2017, the entire disclosures of which are hereby incorporated by reference in its entirety and for all purposes.

TECHNICAL FIELD OF THE INVENTION

The present invention generally relates to pillows. More particularly, the present invention, disclosed herein, relates to a pillow for ergonomically supporting a user.

BACKGROUND OF THE INVENTION

Pillows have been used since ancient times to improve comfort of individuals while sleeping. Pillows have also addressed the problem of recurring back aches, shoulder pains, and neck aches by improving posture while sleeping. Over the years, pillows have been used for both decorative and orthopedic purposes. For instance, throw pillows are used to beautify or improve the aesthetics of the living room or the bedroom. Alternately, lumbar pillows are designed to support the inward curve of the lower back of an individual thereby alleviating pressure on the lower back. Support pillows, on the other hand, are pillows that help position an individual erect while lying on the floor or on a bed for reading or watching television. As such, support pillows are also termed as "reading pillows".

Typically, support pillows are designed to support the lower to mid spinal area and the arms of an individual. Existing support pillows lack the vertical size required to support the shoulder or neck areas of a user. Additionally, existing support pillows lack a headrest or neck support which provides support to the neck area of the user. A pillow which provides ample support to both the spinal and neck regions of a user simultaneously, is therefore required. Furthermore, it is highly advantageous to a user for the headrest or neck support to be adjustable and removable. A pillow, which has, an adjustable headrest or neck support that is also removable, is required.

Hence, there is a long felt but unresolved need for a pillow, which provides ample support to both the spinal and neck regions of a user simultaneously. Furthermore, there is a need for a pillow, which has an adjustable headrest or neck support that is also removable.

SUMMARY OF THE INVENTION

This summary is provided to introduce a selection of concepts in a simplified form that are further disclosed in the detailed description of the present invention. This summary is not intended to identify key or essential inventive concepts of the claimed subject matter, nor is it intended to determine the scope of the claimed subject matter.

The present invention, disclosed herein, addresses the above-mentioned need for a pillow, which provides ample support to both the spinal and neck regions of a user

2

simultaneously. Furthermore, there is a need for a pillow, which has an adjustable headrest or neck support that is also removable.

It is an object of the present invention to provide a pillow that can support the spinal and neck regions of a user. Further, it is an object of the present invention to provide a pillow having an adjustable and removable headrest or neck support. Moreover, it is an object of the present invention to provide a pillow having multiple storage compartments for storing one or more objects.

The present invention provides a pillow for ergonomically supporting a user including a central supporting pillow having at least two arm support members extending from the central supporting pillow. The pillow also includes an adjustable neck support member being cylindrical in shape and having an outer surface, and a bungee cord attached to the neck support member and the central support pillow. The neck support member is freely adjustable and detachably attached using the bungee cord. The bungee cord has one end attached to a top surface of the central supporting pillow and another end attached to the outer surface of the adjustable neck support member to ergonomically support a back and a neck of the user.

The present invention also provides a pillow for ergonomically supporting a user including a central supporting pillow having at least two arm support members extending from the central supporting pillow. The pillow also includes an adjustable neck support member being cylindrical in shape and having an outer surface, and a bungee cord attached to the neck support member and the central support pillow. The neck support member is freely adjustable and detachably attached using the bungee cord. The bungee cord has one end attached to a top surface of the central supporting pillow and another end attached to the cylindrical portion of the adjustable neck support member to ergonomically support a back and a neck of the user.

The present invention further provides a pillow for ergonomically supporting a user including a central support pillow, at least two arm support members, and a neck support member. The central support pillow includes a front surface, a rear surface, a top surface, and a bottom surface. The front surface of the central support pillow is configured to contact a back of the user and conform to the back of the user. The two arm support members extend outward from the front surface of the central support pillow and the at least two arm support members are positioned proximal to the bottom surface of the central support pillow to support arms of the user. The neck support member has a cylindrical portion and opposing end portions and an elongated attachment member having one end attached to the cylindrical portion of the neck support member and another end detachably attached to the top surface of the central support pillow. The neck support member is freely adjustable and detachably attached using the attachment member relative to a top surface of the central supporting pillow to ergonomically support a neck of the user.

In an embodiment, the pillow, disclosed herein, for ergonomically supporting a user includes a central support pillow, at least two arm support members, and a neck support member. The central support pillow includes a front surface, a rear surface, a top surface, and a bottom surface. The front surface of the central support pillow is configured to contact the back of the user and conform to the back of the user. The arm support members extend outward from the front surface of the central support pillow. Additionally, the arm support members are positioned proximal to the bottom surface of the central support pillow to support arms of the

user. A plurality of storage compartments is configured on the at least two arm support members and the central support pillow for storing one or more objects. The neck support member is detachably attached to a top surface of the central support pillow to support a neck of the user. The central support pillow, the at least two arm support members, and the neck support member ergonomically support the back, the neck, and the arms of the user respectively.

BRIEF DESCRIPTION OF THE FIGURES

The foregoing summary, as well as the following detailed description of the present invention, is better understood when read in conjunctions with the appended drawings. For the purpose of illustrating; the present invention, exemplary constructions of the present invention are shown in the drawings. However, the present invention is not limited to the specific methods, components, and structures disclosed herein. The description of a method step, a component, or a structure referenced by a numeral in a drawing is applicable to the description of that method step, component, or structure shown by that same numeral in any subsequent drawing herein.

FIG. 1 is a top, front, right perspective view of a pillow, showing a new design, according to an embodiment of the present invention.

FIG. 2 is a front view thereof.

FIG. 3 is a right side view thereof.

FIG. 4 is a left side view thereof.

FIG. 5 is a rear view thereof.

FIG. 6 is a top view thereof.

FIG. 7 is a bottom view thereof.

FIG. 8 is a top, front right perspective view thereof with a head pillow portion or neck support member positioned downwardly from that shown in FIG. 1.

FIG. 9 exemplarily illustrates a front perspective view of a pillow, according to an embodiment of the present invention.

FIG. 10 exemplarily illustrates a front elevation view of the pillow of FIG. 9.

FIG. 11 exemplarily illustrates a rear elevation view of the pillow of FIG. 9.

FIG. 12 exemplarily illustrates a right-side elevation view of the pillow of FIG. 9.

FIG. 13 is a front perspective view of the pillow with the neck support member positioned downwardly in a first position from that shown in FIG. 9.

FIG. 14 is a front perspective view of the pillow with the neck support member positioned downwardly in a second position from that shown in FIG. 9.

FIG. 15 is a front perspective view of the pillow with the neck support member positioned downwardly in a third position from that shown in FIG. 9.

FIG. 16 is an enlarged rear perspective view of the pillow with the neck support member in a position from that shown in FIG. 9.

FIG. 17 is an enlarged side perspective view of the pillow with the neck support member in a position from that shown in FIG. 9.

FIG. 18 is an enlarged front perspective view of the pillow with the neck support member being adjusted in a position by a hand of a human operator.

DETAILED DESCRIPTION OF THE EMBODIMENTS

FIGS. 1-8 exemplarily illustrate an ornamental design for a pillow, according to an embodiment of the present invention.

FIG. 9 exemplarily illustrates a front perspective view of a pillow 100, according to an embodiment of the present invention. FIG. 10 exemplarily illustrates a front elevation view of the pillow 100. The pillow 100 for ergonomically supporting a user includes a central support pillow 101, at least two arm support members 102, and a neck support member 103. The central support pillow 101 includes a front surface 101a, a rear surface 101b, a top surface 101c, and a bottom surface 101d. In an embodiment the exterior of the central support pillow 101, the arm support members 102, and the neck support member 103 is made of a natural or synthetic fiber, for example, polyester, rubber, cotton, etc. Further, the interior of the central support pillow 101, the arm support members 102, and the neck support member 103 are made of filler materials, for example, foam, cotton, poly-fill, memory foam, Styrofoam beads, etc. The filler materials may also include a combination of gases and foam or only include gases. In one embodiment, the neck support member 103 is generally cylindrical in shape. In one embodiment, the neck support member 103 has a cylindrical portion 103a extending axially and end portions 103b at each axial end of the cylindrical portion 103a. The neck support member 103 also has an outer surface 103c and a zip fastener or zipper 103d (FIG. 16) along the outer surface 103c to allow the filler materials to be removed from an interior thereof. The central support pillow 101 and the arm support members 102 are a single compact unit and the external fiber provides an airtight seal to the filler material contained within.

The front surface 101a of the central support pillow 101 is configured to contact the back of the user and conform to the back of the user. The at least two support members 102 extend outward from the front surface 101a of the central support pillow 101. In an embodiment, the at least two arm support members 102 are positioned proximal to the bottom surface 101d of the central support pillow 101 to support the arms of the user. A plurality of storage compartments 104 is configured on the at least two arm support members 102 and the central support pillow 101 for storing one or more objects as exemplarily illustrated in FIGS. 11 and 12. The neck support member 103 is detachably attached to a top surface 101c of the central support pillow 101 to support a neck of the user. The front surface 101a of the central support pillow 101, the at least two arm support members 102, and the neck support member 103 ergonomically support the back, the arms, and the neck of the user respectively to provide a comfortable position when a user is laying down or partially seated. In an embodiment, the arm support members 102 are positioned at an angle, for example, around 90-120 degrees, relative to the central support pillow 101.

FIG. 11 exemplarily illustrates a rear elevation view of the pillow 100. FIG. 12 exemplarily illustrates a right-side elevation view of the pillow 100. In an embodiment, the storage compartments 104 are configured on the rear surface 101b of the central support pillow 101 and the outer surfaces of the arm support members 102 as exemplarily illustrated in FIGS. 11 and 12. The storage compartments 104 store one or more objects, for example, headphones, e-book readers, laptops, remotes of nearby appliances, spectacles, etc. The storage compartments 104 may be open pouches or pockets or sealable compartments having zip fasteners to seal the storage compartment 101. The neck support member 103 is detachably attached to the top surface 101c of the central support pillow 101. In an embodiment, the neck support member 103 is adjustable and detachably attached using one or more attachment members 104 such as snap fasteners,

hook and loop fasteners, bungee cords, or drawstrings. In an embodiment, the attachment members 104 are elongated. In an embodiment, the attachment members 104 are flexible and may be stretchable. The pillow 100 may include a closed loop or handle 105 attached by a suitable mechanism such as stitching to the central support pillow 101. The pillow 100 may entirely be housed within a removable fabric cover that can be washed periodically to prevent dirt from accumulating on the surface of the pillow 100.

As illustrated in FIG. 13, the neck support member 103 is adjusted relative to the top surface 101c of the central support pillow 101 and positioned downwardly in a first position from that shown in FIG. 9. As illustrated in FIG. 14, the neck support member 103 is adjusted relative to the top surface 101c of the central support pillow 101 and positioned downwardly in a second position from that shown in FIG. 9. As illustrated in FIG. 15, the neck support member 103 is adjusted relative to the top surface 101c of the central support pillow 101 and positioned downwardly in a third position from that shown in FIG. 9. It should be appreciated that the neck support member 103 may be adjusted to other positions relative to the top surface 101c of the central support pillow 101 than that illustrated.

Referring to FIGS. 14-18, the pillow 100 includes one or more anchors 106 at fixed positions on the central support pillow 101. In one embodiment, the anchors 106 may be a button attached by a suitable mechanism such as stitching to the central support pillow 100. As illustrated in FIG. 14, the anchors 106 are at fixed positions along a seam of the central support pillow 101. As illustrated in FIG. 15, the anchors 106 are at fixed positions along the top surface 101 and a side surface of the central support pillow 101. As illustrated in FIG. 16, the attachment members 104 are attached to the anchors 106 by looping around the anchors 106. In one embodiment, the pillow 100 may include an adjuster 107 on the attachment member 104 to allow an adjustable length of the attachment member 104. As illustrated in FIG. 17, the attachment member 104 may be fixed in length by a suitable mechanism such as stitching such that the end of the attachment member 104 extends beyond the anchor 106. As illustrated in FIG. 18, the attachment member 104 may extend through the adjuster 107 and a hand of a human operator may be used to compress the adjuster 107 and allow the length of the attachment member 104 to be adjusted to remove or apply the attachment member 104 about the anchor 106. It should be appreciated that when the adjuster 107 is released by the hand of the human operator the length of the attachment member 104 is fixed.

The foregoing examples have been provided merely for the purpose of explanation and are in no way to be construed as limiting of the integrated pillow 100, disclosed herein. While the integrated pillow 100 has been described with reference to various embodiments, it is understood that the words, which have been used herein, are words of description and illustration, rather than words of limitation. Further, although the integrated pillow 100 has been described herein with reference to particular means, materials, and embodiments, the integrated pillow 100 is not intended to be limited

to the particulars disclosed herein; rather, the integrated pillow 100 extends to all functionally equivalent structures, methods and uses, such as are within the scope of the present invention. Although there has been shown and described the preferred embodiment of the present invention, it will be readily apparent to those skilled in the art that modifications may be made there.

What is claimed is:

1. A pillow for ergonomically supporting a user comprising:
a central supporting pillow having at least two arm support members extending from the central supporting pillow;
an adjustable neck support member being cylindrical in shape and having an outer surface; and
a bungee cord attached to the neck support member and the central support pillow, wherein the neck support member is freely adjustable and detachably attached using the bungee cord, the bungee cord having one end attached to a top surface of the central supporting pillow and another end attached to the outer surface of the adjustable neck support member to ergonomically support a back and a neck of the user.
2. The pillow as claimed in claim 1, including a plurality of storage compartments on an exterior of the at least two arm support members and a rear of the central supporting pillow to allow temporary storage of one or more objects.
3. The pillow as claimed in claim 1, wherein an exterior of the central supporting pillow, the at least two arm support members, and the neck support member is made of natural or synthetic fiber comprising one of polyester, rubber, cotton, and leather.
4. A pillow for ergonomically supporting a user comprising:
a central supporting pillow having at least two arm support members extending from the central supporting pillow;
an adjustable neck support member having a cylindrical portion and opposing end portions; and
a bungee cord attached to the neck support member and the central support pillow, wherein the neck support member is freely adjustable and detachably attached using the bungee cord, the bungee cord having one end attached to a top surface of the central supporting pillow and another end attached to the cylindrical portion of the adjustable neck support member to ergonomically support a back and a neck of the user.
5. The pillow as claimed in claim 4, including a plurality of storage compartments on an exterior of the at least two arm support members and a rear of the central supporting pillow to allow temporary storage of one or more objects.
6. The pillow as claimed in claim 4, wherein an exterior of the central supporting pillow, the at least two arm support members, and the neck support member is made of natural or synthetic fiber comprising one of polyester, rubber, cotton, and leather.
